UNITED STATES PATENT OFFICE.

ALBERT BALL, OF CLAREMONT, NEW HAMPSHIRE, ASSIGNOR, BY MESNE ASSIGNMENTS, TO THE JEFFREY MANUFACTURING COMPANY, OF COLUMBUS, OHIO, A CORPORATION OF OHIO.

MINING-MACHINE.

1,365,881.

Specification of Letters Patent. Patented Jan. 18, 1921.

Application filed June 20, 1911, Serial No. 634,293. Renewed April 17, 1920. Serial No. 374,752.

To all whom it may concern:

Be it known that I, ALBERT BALL, a citizen of the United States, and a resident of Claremont, county of Sullivan, State of New Hampshire, (whose post - office address is Claremont, New Hampshire,) have invented an Improvement in Mining-Machines, of which the following description, in connection with the accompanying drawings, is a specification, like characters on the drawings representing like parts.

This invention relates to mining machines and more particularly to coal mining machines intended for cutting a continuous kerf in the side wall of a mine, the invention consisting in improvements for regulating the cut.

It frequently happens that a streak or stratum of slate is encountered part way up the wall and, if the entire wall is undercut, as is usually necessary where the machines now in vogue are employed, considerable trouble and expense is entailed in separating the slate from the coal. In the dis- closed form of machine I have provided means whereby the kerf can be caused to follow the higher level of such a stratum of slate. By this means the coal below the slate can first be undercut and broken down and the layer of slate then cut out, after which the coal above the slate can be broken down. Such method of removal is much cheaper and quicker than that formerly in use.

The invention will be best understood by reference to the following description when taken in connection with the accompanying illustration thereof, while its scope will be more particularly pointed out in the appended claims.

In the drawings:

Figure 1 is a plan view of the auxiliary shoe or support which is employed in the disclosed embodiment of the invention;

Fig. 2 is a side elevation of the auxiliary shoe showing the lower part of the mining machine sustained thereby, the upper portion being broken away;

Fig. 3 is a front elevation of the shoe and machine as shown in Fig. 2;

Fig. 4 is a plan view, and

Fig. 5 an elevation of one of the side rests of the auxiliary support;

Fig. 6 is a plan view partly diagrammatic

showing a mining machine mounted upon the support shown in Fig. 1; and

Fig. 7 is a side elevation of the mining machine shown in Fig. 6.

Referring to the drawings and to the embodiment of the invention therein disclosed, while it may be usefully employed in connection with other types of mining machines, I have shown the same as applied to a self-propelled machine of the long wall type employed for cutting a continuous kerf in the side wall of the mine. For the sake of illustrating one concrete form of the invention, a machine is shown of the well known cutter-chain type provided with the cutter bar 1 projecting therefrom and adapted to undercut the wall of the mine while moving in the direction of the arrow shown in Fig. 6. The cutter bar, as usual, is provided with cutting appliances consisting of the endless cutter chain 2, the latter being driven from the sprocket wheel indicated at 3. The sprocket wheel 3 is driven by any suitable motor carried by the machine such as the electric motor indicated at 4.

While any suitable construction may be employed for traversing the machine while cutting, in the present instance supporting means are provided, upon and with which the machine is adapted to move along the mine. Preferably, as in the machine of the prior patent to Mitchell No. 656,414, such means is provided in the form of a bottom plate or shoe 5 to which the body of the machine is rigidly secured and upon which it is adapted to slide, if required, directly upon the bottom or floor of the mine.

To hold the cutter chain and the cutter bar in the desired relation against the work as the machine is fed along, guiding means are provided, the same consisting of one or more ropes, cables or flexible guiding members kept under tension and preferably so associated with the machine that the cutter bar as it travels is held up to the work without the necessary use of rails or other like guiding supports.

In the illustrated form of the invention I provide for this purpose flexible guiding means, herein consisting of a cable chain 6, which, in the utilization of the machine, is connected to fixed supports, one on the advancing side of the machine and the other on the receding side thereof, one part of the

chain being connected to the machine relatively near its wall or cutting end and the other near the opposite end thereof.

In the disclosed machine (see Figs. 6 and 5 7) the cable chain 6 in making the main or lateral cut is connected to the fixed anchor 7 at the end of the wall. The anchor 7 may be of any suitable construction such as that shown in the aforesaid Mitchell patent. The 10 opposite end of the chain is connected to a fixed support 8 at the receding side of the machine. In order to take in or let out the chain the support 8 may be in the form of an adjustable take-up jack having, for example, a construction similar to that of the take-up jack shown in Figs. 16 and 17 of the aforesaid Mitchell patent.

At the forward end of the machine the chain is connected thereto by passing about 20 the guide sheave 9 journaled on the machine, thence about the sheaves 10 and 11. It thence passes toward the rear end of the machine about the sheave 12, thence about a sprocket wheel 13, leaving the machine at the guide 25 sheave 14 carried on the arm 15. The chain is so connected to the machine by the relation of the guide sheaves 14 and 9 that, when placed under tension with the cutter-chain in position against the work, it tends to swing 30 the cutter bar forward against the work about the fulcruming guide sheave 9 and, as the machine travels, serves to hold the cutter bar up to the work. The tendency to hold the machine to the work, which is effected 35 by the leverage or pull of the guide chain is assisted by a slight forward inclination of the cutter bar. The position of the machine can be regulated more or less by taking in or letting out the receding end of the chain 40 at the jack 8 to swing the machine more or less about the guide sheave 9 as a fulcrum.

The guide chain 6 is herein utilized also as a feed chain, the machine being self-propelled. To accomplish this the sprocket 45 wheel 13 is driven by the motor 4 so that the machine pulls itself along on the chain. The sprocket wheel is connected to be driven by the motor through any suitable transmission devices, not herein shown, but 50 which may be similar to those illustrated in the Mitchell patent.

The machine as described may be operated with the shoe 5 resting upon the mine bottom and caused to pull itself along and 55 cut a continuous kerf at substantially the level of the floor. When it is required to cut a kerf at a higher level, the entire machine is placed upon an auxiliary support shown in Figs. 1 to 3, which auxiliary support 60 is provided with the bottom plate or shoe 16 similar to the shoe 5 of the mining machine and also with means for securing the mining machine rigidly to the auxiliary support so that the machine may be traversed with its cutter bar at an elevated posi-

tion but, by means of the guiding and feeding chain 6 and in precisely the same manner as if resting upon its own bottom plate and as represented in Figs. 6 and 7.

Referring to Figs. 1 to 5, inclusive, the auxiliary shoe 16 consists of a plate of steel or other suitable material substantially co-extensive in length and width with the mining machine which it is to support and having its ends slightly curled or turned up so as to ride over slight obstructions. To the upper side of the shoe there are riveted or otherwise secured channel irons 17 and 18 which reinforce the sides of the shoe and provide a firm foundation for elevating jacks having columns or pedestals 19 and 20 bolted to the channels 17 and 18, respectively, near one end of the shoe. Each column is interiorly threaded and receives a jack screw 21 having the head 22 whereby it may be turned by any suitable implement and carries at its top the plate 23 in swiveled relation to the screw. Each plate is perforated to receive clamping bolts as shown and the underside of the mining machine 25 shoe 5 is tapped at appropriate points to receive the said bolts so that the mining machine can be bolted in fixed relation to the jack screw plates 23.

Transversely across the opposite end of the shoe there is also provided a reinforcing channel iron 24, to the center of which is bolted the column 25 of a jack screw similar to those already described. This column is also provided with the screw 26 and a plate 27 adapted to be bolted to the opposite end of the mining machine shoe.

The columns 19, 20 and 25 which support the mining machine in elevated position are very rigidly braced so that the fixed relation 105 of the mining machine to the auxiliary shoe cannot be disturbed. To brace the columns 19 and 20 laterally there is provided a stay member 28 which is bolted to the lugs 29 and 30 on the sides of the columns, there being also provided longitudinal stays 31 and 32 riveted to the sides of the channels 17 and 18 respectively, and serving to brace the columns 19 and 20. The column 25 at the opposite end in turn is laterally braced 115 by means of the angle braces 33 and 34. As is shown in the drawings, devices 35 are preferably provided bolted to the sides of the channel irons 17 and 18 so as to provide convenient means for lifting the auxiliary 120 support or prying it around from one position to another.

The three jack screws described provide three points of support for the mining machine, supplying a firm and rigid foundation therefor. By means of the jack screws the three points on the mining machine shoe to which the jack screw plates are attached can be raised or lowered as required until the cutter bar is at the required level. By 130

adjusting the two rear jack screws the inclination or dip of the cutter bar also can be adjusted.

To further stiffen the end of the mining machine on either side of the jack screw 26, auxiliary attachments are provided thereat which can be adjusted to and clamped to the underside of the mining machine shoe after the latter has been brought to the required level by the jack screws. Herein, as shown in Figs. 4 and 5, the auxiliary attachments comprise a pair of blocks 36 one at each side of the jack screw 26, such blocks being adapted to be bolted to the under side of the shoe 5. Each block is pivotally connected to one of a pair of coöperating links 37, and the ends of the links 37 remote from said pivotal connections are slotted and adapted to receive a clamping bolt 38 mounted in the pedestal 25, whereby, upon adjustment of the jack screw 26, the links may be bolted in rigid relation to the pedestal 25 and so brace the mining machine in its position relative to the shoe 16. The sides of the blocks are jointed each to one of a pair of longitudinally extending links 39, the opposite ends of which links are provided each with a slot which receives a clamping bolt 40, the latter being threaded into the end of a transverse tie member 41 which is fixed between the brace members 31 and 32. When the mining machine is adjusted on the jack screws as described, the bolts 38 and 40 are loosened. The blocks 36 will be understood to be bolted to the under side of the mining machine shoe, so that when the bolts 38 and 40 are tightened they brace the mining machine rigidly in elevated position on the under or auxiliary shoe 16.

While I have herein shown for the purpose of illustration one specific form of the invention, it is to be understood that the same is not limited to the constructional details herein shown or to the specific application herein made. It is to be understood that not only may the described details of construction and arrangement of parts be widely deviated from without departing from the principles of the invention, but that other applications of the invention may be made and other embodiments thereof employed.

Claims:

1. Mining apparatus comprising, in combination, a flexibly fed, offset positioned mining machine having a shoe on which it is normally fed along the mine bottom to cut a kerf adjacent the floor of the mine, and an auxiliary shoe on which said mining machine may be mounted and with which said mining machine may be flexibly fed and flexibly positioned for cutting a kerf at a higher level.

2. In a mining machine for cutting a continuous kerf, the combination with cutting mechanism, motive means for propelling the

machine, a bottom plate on and with which the machine is propelled by said motive means during the cutting operation, of an auxiliary bottom plate on which the machine may be propelled by said motive means during cutting operations with its cutting mechanism at a higher level, and means for detachably attaching said auxiliary supporting means to the bottom of the first named means.

3. A mining machine having a shoe to support the same on the floor of the mine and cutting mechanism for cutting a continuous kerf at a given level, self propelling means for said mining machine, an auxiliary support for said machine on which the cutting mechanism is adapted to cut a kerf by operation of said cutting means at a higher level, and means for rigidly securing said support to said machine to enable the latter to travel upon and with the support when cutting at said higher level.

4. In a mining machine, the combination with cutting mechanism for cutting a kerf at a given level, of an auxiliary support on which said mining machine may be supported and with which said mining machine may be progressed during cutting movement with said cutting mechanism at a higher level, and means for detachably securing said auxiliary support to the bottom of the mining machine.

5. In a mining machine, the combination with cutting mechanism for cutting a kerf at a given level, of an auxiliary support comprising a skid disposed in a horizontal plane on which the mining machine may be supported and with which said mining machine may be progressed during cutting movement with its cutting mechanism at a higher level for cutting a higher kerf, and means for detachably securing said auxiliary support to the bottom of the mining machine.

6. In a mining machine, the combination with a support and cutting mechanism for cutting a kerf at a given level, of an auxiliary support on which the mining machine may be supported and with which said mining machine may be progressed during cutting movement with its cutting mechanism at a higher level for cutting a higher kerf, means for detachably securing said auxiliary support to the bottom of the mining machine, and means for varying the effective height of said auxiliary support.

7. Mining apparatus comprising, in combination, a mining machine having a shoe 5 on which said mining machine slides on the mine bottom when cutting a kerf at a given level; an auxiliary support having an auxiliary shoe 16 on and with which the machine is adapted to travel along the mine bottom when cutting a kerf at a higher level, and a plurality of elevating jacks 19, 20, 25

supported on said auxiliary shoe and adapted to support said mining machine at a plurality of operating levels relative to said auxiliary shoe.

5. 8. Mining apparatus comprising, in combination, a mining machine having a shoe 5 on which said mining machine slides on the mine bottom when cutting a kerf at a given level; an auxiliary support having an 10 auxiliary shoe 16 on and with which the machine is adapted to travel along the mine bottom when cutting a kerf at a higher level, a plurality of elevating jacks 19, 20, 15 25 supported on said auxiliary shoe and adapted to support said mining machine at a plurality of operating levels relative to said auxiliary shoe, and braces 31, 39 for said jacks.

9. A mining machine support comprising, 20 in combination, upper and lower members, the latter being adapted to travel along the mine bottom, a pair of elevating jacks connecting said members adjacent one end thereof, a single elevating jack connecting 25 said members adjacent the opposite end thereof, a pair of rigid braces for said pair of jacks, a pair of angularly adjustable braces pivoted to one member, means adjustable to secure said adjustable braces to 30 said rigid braces, a pair of angularly adjustable braces pivoted to one of said members, and means adjustable to secure the last-mentioned braces to said single jack.

10. A mining machine support comprising, 35 in combination, upper and lower members, the latter being adapted to travel along the mine bottom, a pair of elevating jacks each comprising an internally threaded column and a co-operating screw, a pair of 40 rigid braces for said columns, a pair of angularly adjustable braces pivoted to one member, means adjustable to secure said braces in fixed position with relation to the other member, a third elevating jack comprising 45 an internally threaded column and a co-operating screw, rigid brace means for the column of said third jack, a pair of angularly

adjustable braces pivoted to one of said members, and means adjustable to secure the last-mentioned pair of braces rigidly with 50 respect to the other member.

11. In a mining apparatus, a vertically adjustable mining mechanism in a relatively elevated position, a shoe extending continuously under the mining mechanism and adapted to rest directly upon, and to move universally over, a mine floor, and a series of extensible pillars supported on the shoe and flexibly secured directly to the underside of the mining mechanism. 60

12. In a mining apparatus, a vertically adjustable mining mechanism normally positioned in relatively elevated planes, a shoe extending continuously over a horizontal area substantially equal to that of the mining 65 mechanism, a series of extensible pillars on the shoe, each having a bottom element directly connected to the shoe and a top element directly connected below and to the underside of the mining mechanism, and a 70 movable element adjustably connected to the said bottom element and flexibly connected to the top element.

13. In a mining apparatus, a mining mechanism positioned in relatively elevated 75 planes, a shoe below it resting on and universally movable over a mine floor, two vertically extensible pillars secured to one end of the shoe and supporting one end of the mining mechanism, and a third vertically 80 extensible pillar under the central part of the opposite end of the mining mechanism and bearing directly upward against the under-side thereof, all of said pillars being within the bounding vertical planes of the 85 mining mechanism and each being vertically extensible independently of the others.

In testimony whereof, I have signed my name to this specification, in the presence of two subscribing witnesses.

ALBERT BALL.
